BARREL WASHING MACHINE

Carl J. Schroeder, Hobart, Ind., assignor to
Standard Oil Company, Chicago, Ill., a corpora-
tion of Indiana

Application June 30, 1933, Serial No. 678,387

11 Claims. (Cl. 141—6)

My invention relates to improvements in automatic barrel washing machines.

An object of my invention is to provide an automatic barrel washing machine wherein a plurality of barrels may be progressively conveyed in groups through a series of stages, each stage providing a separate function in the complete barrel washing and rinsing operation.

Another object is to provide an automatic barrel washing machine wherein all the stages are simultaneously operated, each treating the group of barrels conveyed thereto from the next preceding stage.

A further object is to provide, in an automatic barrel washing machine, mechanism for simultaneously moving the entire entrainment of barrels through a distance equal to one stage length, and for positively stopping the conveyor at a predetermined position whereby the barrels in certain of the stages may bear exact relationships with internal spraying nozzles adapted to enter the barrels through the barrel bung holes.

Another object is to provide an automatic barrel washing machine wherein damage to the barrel conveyor driving mechanism through the accidental jamming or stalling of the barrel conveyor chain is precluded.

A further object is to provide an automatic barrel washing machine wherein the introduction of the internal barrel spraying nozzles into the barrels may not take place until after movement of the barrels by the conveyor has ceased.

A still further object is to provide a novel internal spraying nozzle of the swing pipe type for uniformly distributing washing solution or rinsing water to the interior walls of the barrel.

Other objects, the advantages, and uses of the invention will become apparent after reading the following specifications and claims, and after consideration of the drawings forming a part of this specification wherein:

Fig. 1 is a schematic top plan view of an automatic barrel washing machine constructed in accordance with my invention;

Fig. 2 is a schematic section of the mechanism illustrated in Fig. 1;

Fig. 3 is a chart representing a complete cycle of operation of the barrel washing machine;

Fig. 4 is a flow diagram of the preheating, washing and rinsing fluids employed;

Fig. 5 is a diagrammatic view illustrating the electrical and hydraulic control circuits and flow lines employed in the barrel washing machine;

Fig. 6 is a top plan view of the conveyor chain grip;

Fig. 7 is a sectional view along the line VII—VII of Fig. 6;

Fig. 8 is a sectional view along the line VIII—VIII of Fig. 6;

Fig. 9 is a fragmentary top plan view of a part 5 of the mechanism illustrated in Fig. 7;

Fig. 10 is a fragmentary top plan view of the retardation mechanism for the chain grip;

Fig. 11 is a sectional view along the line XI—XI of Fig. 10;

Fig. 12 is a sectional view along the line XII—XII of Fig. 11;

Fig. 13 is a vertical sectional view substantially along the line XIII—XIII of Fig. 2;

Fig. 14 is a view partly in elevation, and partly 15 in section, of one of the swing pipe nozzles;

Fig. 15 is a top plan view of the nozzle of Fig. 14;

Fig. 16 is a sectional view along the line XVI—XVI of Fig. 14;

Fig. 17 is a top plan view of the swing pipe nozzle spraying mechanism of stage 6;

Fig. 18 is a sectional view along the line XVIII—XVIII of Fig. 17;

Fig. 19 is a vertical elevation of the automatic 25 switch mechanism employed for controlling conveyor chain movement and movement of the swing pipe nozzles;

Fig. 20 is a top plan view of the switch mechanism of Fig. 19;

Fig. 21 is a sectional view along the line XXI—XXI of Fig. 20;

Fig. 24 is a sectional view through the conveyor mechanism illustrating the operating means for the carriage speed control switch;

Fig. 25 is a horizontal sectional view through 40 the conveyor housing illustrating the control mechanism for the carriage limit switch;

Fig. 26 is a diagrammatic view of a modified form of the carriage and nozzle operating mechanism operated entirely by hydraulic means, and 45

Fig. 27 is a fragmentary diagrammatic view of the pressure control mechanism for the hydraulically operated conveyor pump.

I have selected for illustration (Figs. 1 to 25 inclusive) an automatic barrel washing machine 50 wherein the controlling and the synchronizing of the barrel conveyor mechanism and of the rising and receding of the swing pipe spray nozzles is accomplished by means of a comparatively simple electrical circuit, and in Fig. 26 in sche- 55

matic view, I have illustrated a modified form of the washing machine wherein the automatic control and synchronization of the various moving parts, of the machine is accomplished by hydraulic means. In both embodiments of the invention the movement of the barrel conveyor chain is carried out by hydraulic driving means.

With reference to Figures 1 and 2, the barrels BB are carried through the washing machine up on an endless conveyor chain 10 supported at its opposite ends upon idler drums one of which is shown at 11. The conveyor chain 10 passes through an elongated metal housing 12 within which preheating, washing and rinsing nozzles are located. During the complete washing and rinsing operations the barrels pass in groups of four successively through eight separate stages, six of the stages, 2 to 7, inclusive, (see Fig. 2) being located within the housing 12. Stage 1, at the forward end of the housing, is set apart for the loading of the barrels BB upon the chain. This may be done by manual labor or by automatic means (not shown). Stage 8, located beyond the rearward end of the housing 12, is set apart for the unloading of the barrels from the chain for dehydration or any desired usage or disposal. The movement of the barrel through the successive stages is in the direction of the arrow 13.

Functions of the successive stages

Stage 1—Loading of barrels upon the conveyor chain.

Stage 2—Barrels are sprayed externally through spray nozzles 14 with water at approximately 180° F., previously pumped from the rinsing reservoir of stage 6 as will be hereinafter described. This preheating operation functions to loosen the cake of dirt and grease ordinarily present on the outside of barrels and the heat transmitted to the inner walls of the barrels tend to soften and loosen grease deposits therein in preparedness for the washing operation.

Stage 3—The preheating water is permitted to drain from the outside of the barrels back to the reservoir 15 of stage 2.

Stage 4—The barrels are washed externally through spray nozzles 16 and internally through swing pipe nozzles 17 with a hot caustic solution at substantially 185° F. and at a pressure of from 80 to 125 lbs. per square inch. Excess caustic solution may flow back into the reservoir 18.

Stage 5—The caustic solution from the inside and outside of the barrels is permitted to flow back into the reservoir 18 of stage 4.

Stage 6—The barrels are rinsed externally through nozzles 19 and internally through swing pipe nozzles 20 with hot filtered water at 185° F. and at a pressure of from 80 to 125 lbs. per square inch. The excess rinse water may flow into the reservoir 21 where a part of it may be pumped, as will be hereinafter described, into the preheating reservoir 15 of stage 2. Pure filtered water is admitted to stage 6 through the swing pipe nozzles 20 for internal washing of the barrels, the water employed for the nozzles 19 being water from the reservoir 21.

Stage 7—The hot rinse water is permitted to drain back into the reservoir 21.

Stage 8—Unloading for dehydration, etc.

A better understanding of the handling of the preheating, washing and rinsing solutions may be had from a study of the flow diagram of Fig. 4 wherein it may be seen that the preheating water of stage 2 is conducted to the reservoir 15

from the reservoir 21 of stage 6 through a pump 25 and interconnecting pipe 26. The water for the nozzles 14 is withdrawn from the reservoir 15 by a pump 27. Inasmuch as water is being constantly conducted to the reservoir 15 from the rinse water reservoir 21 a part of the old water of the reservoir 15 may be removed by a pump 28 through a heat exchange device 29 and thereafter conducted to a settling box 30 having its outlet 31 in communication with the sewer. This method of handling the used preheating water is employed as an aid in heating the filtered water for stage 6. Rinsing water obtained from a supply pipe 33 is passed through filters 34 through the heat exchanger 29 into a heating tank 35 having a steam heating coil 36 where it is heated to the proper temperature for the rinse and is thereupon pumped directly to the swing pipe nozzles 20 through the medium of a pump 37 actuated, as will be hereinafter described, only during the entry of the nozzles within the barrels. A pump 38 is employed for withdrawing rinsing water from the reservoir 21 for the rinsing nozzles 19.

The caustic solution for stage 4 is provided by admitting concentrated caustic solution from a tank 41 into a water feed pipe 42, carrying water which has been previously heated to the required temperature by a steam heating coil 43 in a heating tank 44. The caustic washing solution so formed is admitted directly to the reservoir 18 of stage 4 where it may be pumped by a pump 45 to the external spray nozzles 16 and swing pipe nozzles 17.

The reservoirs 15, 18 and 21 are each connected through shut-off valves V with a pump 47 whereby the sedimentary water or solution from the bottoms of the reservoirs may be pumped directly into the settling box 30 when desired.

Conveyor chain operating mechanism

With reference particularly to Figs. 2 and 6 to 12, inclusive, the conveyor chain 10 comprises a plurality of pairs of parallel links 51 having pivotal connection with the next adjacent pairs and provided with flanged wheels 52 at their points of interconnection adapted to ride upon horizontally disposed rails 53 extending the full length of the conveyor between the idler drums 11. The lower part of the conveyor chain is permitted to ride upon channels 54 during return travel. The barrels BB may rest directly upon the upper edges of the links 51. Inasmuch as each of the stages 2 to 7, inclusive, occupy linearly equal and adjacent portions of the housing 12, it is necessary to move the conveyor chain 10 during each complete cycle of operation of the machine an amount equal to one stage length thereby bringing the barrels from stage 2 on to stage 3 and the barrels of stage 3 to stage 4, etc.

For this purpose the conveyor chain grip illustrated in Figs. 6 to 12 is provided. The chain grip is constructed after the fashion of a carriage and consists of a pair of channels 56 with their backs facing one another and spaced apart by sleeves 57. Wheels 58 are provided at the outer sides of the channels 56 and arranged to ride upon the lower flanges 59 of a pair of opposed channel irons 61 forming a track along which the chain grip may move.

An hydraulically operated piston 63, operating in an elongated cylinder 64, is employed to move the chain grip a distance substantially equal to one stage length and to draw the grip in the direction of the arrow 13 (Fig. 2), together with the

conveyor chain an amount exactly equal to one stage length. The piston 63 is coupled to the chain grip through a lost motion connection comprising a rod 65 fixed to the piston and extending forwardly through a collar 66 fixed between the channels 56 of the chain grip and secured by threaded engagement 67 to a block 68 slidably supported between the channels 56. When the piston is drawn inwardly of the cylinder 64 during the advance of the conveyor chain 10 as described the block 68 may abut the collar 66 to provide a positive draft connection. When the piston 63 is moved inwardly of cylinder 64 the block 68 will advance relative to the collar 66 and to the channels 56 and in so doing will cause a driving dog 69, pivotally mounted at 71 between the channels 56, to rise upwardly in the path of the conveyor chain so that its outer end lies in the plane of the adjacent spacer sleeve 72 between the pairs of chain links 51. This elevation of the dog 69 is caused by the presence of a relatively short link 73 having pivotal connection at 74 with the outer end of the dog 69 and at 75 with the block 68. In Fig. 7 I have illustrated the position of the dog 69 as it appears during the movement of the conveyor chain by the hydraulic piston 63 and in dotted line the dog 69 is shown as it appears during the return movement of the chain grip in the direction of the loading stage of the machine.

Fig. 7 further represents the chain grip as it appears at the end of its draft movement wherein the conveyor chain stop 81, pivotally mounted at 82 upon the support 83 provided for on the forward end of the cylinder 64, is illustrated in its chain engaging position. The stop 81 normally lies in the position shown in dotted lines in Fig. 7. It is formed at its outer end with a stirrup 84 which embraces the outer side walls of the channels 56. As shown in Fig. 8, cam members 85 and 86 secured to the outer walls of the channels 56 form an inclined guideway 87 within which rollers 88 rotatably mounted on the inner and opposed walls of the stirrup 84 may at times ride. The chain stop 81 is caused to rise to the position shown in full lines in Figs. 7 and 8 when the chain grip has completed its function of advancing the conveyor chain and will fall downwardly to its dotted line position when the chain grip is urged away from the cylinder 64 during its return stroke. A stop in the form of a Z-bar 89 may be provided to arrest the return movement of the chain stop 81 so that the rollers 88 will lie in the path of the guideways 87 when the chain grip next completes its chain draft movement.

In order that the chain grip may not start on its return movement prior to the lowering of the dog 69 to the dotted line position of Fig. 7 a latch 91 is pivotally mounted at 92 between the channels 56 and beneath the dog 69. The latch is so balanced upon its axis of rotation that it will tend to assume the position shown in Fig. 7 with its forward end disposed in the path of a stationary stop member 93. Return movement of the chain grip is therefore precluded by the abutment of the latch 91 against the stop 93 until such time as the dog 69 is lowered through the instrumentality of the link 73 and the lost motion connection between the piston 63 and the chain grip.

In Figs. 10 and 12 I have illustrated mechanism for retarding the chain grip so that the piston 63 may move relative to the chain grip and thus assure the elevation of the dog 69 to the position shown in Fig. 7 prior to the advance 75 of the chain grip, the purpose being to effect

a positive driving engagement between the chain grip and a spacer sleeve 72 of the chain. This mechanism consists of a tongue 95 fixed at the forward end of the chain grip between the channels 56 and is formed with a wedge-shaped enlarged head 96. The tongue 95 is adapted to enter between a pair of rollers 97 mounted upon a pair of frames 98 respectively. Each of the frames 98 is pivotally mounted at 99 upon a stationary supporting assembly 101. A pair of compression springs 102 are employed to draw the frames 98 toward one another and hence the rollers 97 into close engagement with the tongue 95. The springs are so adjusted as to yield to the spreading of the frames 98 under the influence of forces arising by the introduction of the head 96 therebetween at end of the return movement of the chain grip, but are of sufficient strength to retard reverse movement of the chain grip until the lost motion between the piston 63 and the chain grip is taken up accompanied by the resulting elevation of the dog 69 in the manner described. The dog 69 is thus moved into a position where it will engage with the spacer sleeve or tube 72 of the adjacent chain link to draw the chain supporting the barrels BB with the grip on its draft stroke. The mechanism for controlling the hydraulic piston 63 will be hereinafter described:

Barrel interior wash and spray mechanism

In Figs. 13 to 18, inclusive, I have illustrated the mechanism for spraying the interior of the barrels, with caustic solution in stage 4, and with hot rinse water in stage 6. The construction of the swing pipe nozzles and nozzle operating means for the two stages is identical with the exception of slight differences in the fluid connections as has been previously explained under "Functions of the successive stages". The mechanism employed in stage 6 has been selected for illustration because of the inclusion therein of a switch mechanism for controlling the crank shaft and the hydraulic piston 63. As may be seen in Fig. 13 the conveyor chain 10 is located in a plane substantially 10° from horizontal and the housing 12 is similarly canted. This positioning of the conveyor chain and housing 12 fulfills a three-fold purpose. First, that of tilting the barrels BB so that the washing solutions and rinsing water may drain through the bung-holes 105 of the barrels into the housing 12 and from the housing into the adjacent reservoirs 15, 18 or 21 depending upon the stage location of the barrels. Secondly, the tilting of the conveyor chain and barrels BB more readily permits of the introduction of the swing pipe nozzle assemblies 17 or 20 within the barrels by effecting a lowering of the center about which the swing pipe nozzles are mounted, and thirdly, more adequate draining of the concave top of the barrels.

As may be seen the stationary nozzles represented at 19 and 19A in Fig. 13 for stage 6 are located in such a position within the housing 12 as to distribute a spray of fluid over the exterior of the barrels with substantial uniformity. The distributing heads 106 of the swing pipe nozzles are located at the outermost ends of the arcuate swing pipes 107, there being one pipe 70 for each barrel on the stage. I have illustrated the stages as having a capacity of four barrels each and hence four of the swing pipes 107 are shown for each of the two stages. The pipes 107 are connected to a U-shaped feed pipe 108 75

pivotaly mounted at its opposite ends 109 (see Fig. 17) so that the nozzles may be swung from a position below the barrels through the barrel bung-holes 105 and up to the dotted line position shown in Fig. 13.

The driving means for swinging the nozzles into the barrels and withdrawing the nozzles therefrom comprises a drive shaft 115 extending from one end of the machine adjacent to the 10 unloading stage to stage 4 (see Fig. 1). The drive shaft is arranged to rotate crank shafts 116 through the medium of intermeshing pinions 117 and gears 118 located upon the drive shaft 115 and crank shafts 116 respectively. Each of 15 the crank shafts 116 is provided with crank arms 119 at its opposite ends. The outer ends of the crank arms 119 are connected, by connecting rods 121, to the legs of the U-shaped supply pipes 108 so that one complete revolution of the 20 crank shafts 116 will cause the swing nozzles to move from the position shown in full lines in Fig. 13 to the position shown in dotted lines and return. This portion of the cycle of operation 25 of the machine is represented by the angle 122 in the chart shown in Fig. 3 wherein the time during which the nozzles are in operation is arbitrarily fixed as three-fourths of the time required to carry out a complete cycle of operation of the entire barrel washing machine.

30 In order that the swing pipe nozzles may enter the barrels without difficulty, funnel shaped guide members 125 fixed to the conveyor chain 10 are provided, one for each barrel. The guides 125 may be further used in locating the barrels upon 35 the conveyor chain during the loading operation at stage 1. Tubular guide members 126, fixed to the housing 12, serve to maintain registration between the swing nozzles and the guides 125.

With reference to Figs. 14 to 16 I have illustrated 40 a nozzle or fluid distributing head particularly adapted for use with swing nozzles of the type designed to enter the barrels through bung-holes near the side walls of the barrels and to be moved through the path illustrated 45 in Fig. 13. It will be noted that the nozzle head is divided into three zones, 127, 128 and 129 and that the zones each have passageways 131 extending through their side walls and communicating with the inner bore 132 of the nozzle. 50 The passageways 131 are so distributed as to divide the major discharge of fluid throughout an angular range of 180° about the vertical axis of the head, this portion of the nozzle being turned toward the remote half of the barrel interior. There are but three of the passageways 55 131 extending toward the adjacent side wall of the barrel and one which is upon the vertical axis of the nozzle. I have thus provided a spray nozzle which when moved substantially longitudinally along one portion of the inner wall of a 60 cylindrical barrel will distribute fluid substantially over the entire interior walls of the barrel so that all regions thereof may be adequately washed or rinsed. In Fig. 14 I have designated 65 the angular disposition of the zones 128 and 129 with respect to the axis of the nozzle.

Automatic control of swing pipe nozzles and conveyor chain

70 With reference to Fig. 5 it may be seen that the drive shaft 115 is driven in the direction of the arrow 141 by an electric motor L operating a reduction gear unit 142 through an electro-magnetic clutch K. The shaft 115 may be connected 75 directly to the gear reduction unit 142.

The motor L is intended for continuous operation at all times during the functioning of the barrel washing machine and the speed of the motor is controlled by a rheostat 143. The shaft 115, however, and the driven crank shafts 116 will rotate only so long as the magnetic clutch K is energized. The clutch K is controlled by a spring-loaded switch C which is actuated together with a spring-loaded switch D by an arm 144 normally lying in the path of a cam 145 fixed to the crank shaft 116 of stage 6. In Fig. 5 the arm 144 is shown as shifted out of the path of the cam 145 against the force of a compression spring 146 (see Fig. 19) by a solenoid mechanism M connected in series with a limit switch G and the power line. At this time the switch C is closed. The switch C being closed therefor serves to couple the motor L with drive shaft 115 through the energizing of the clutch K thus to drive the crank shafts 116. The crank shafts (one of which is shown in Fig. 5) are therefore at the beginning of their one revolution cycle during time the swing nozzles will be elevated into the barrels and will thereafter return to the position shown in Fig. 5. The limit switch G located near the cylinder 64 is closed at this time by virtue of the fact that the chain grip is at the end of its draft stroke and has caused a bell crank 147 to swing upon its center 148 to depress the switch actuating push rod 149. Energization of the solenoid M by the closing of the switch G has caused the solenoid plunger 151 to move from its dotted line position to its full line position to shift the arm 144 out of the path of the cam 145 as previously described. Details of the solenoid M and the switches C and D are shown in Figs. 19 to 22, inclusive.

It should be noted that the switches C and D are both operable by rotative movement of a shaft 153 to which the arm 144 is fixed and are so arranged as to cause the switch C to open slightly in advance of the closing of switch D when the arm 144 is raised against the spring loading of the switches as by operation of the cam 145. This adjustment of the switches may be effected either by shifting the switch operating fingers 154 relative to the shaft 153 or by adjustment of the buttons 155 engageable with the switch arms 156. Both of the switches C and D may be enclosed within a casing 157 and submerged in oil. This is of particular importance where the barrel washing machine is to be employed in an oil refinery and it is contemplated that for such use all of the switches included in the diagram of Fig. 5 shall be so protected.

The solenoid M, the switches C and D in the housing 157, and the switch operating arm 144 are mounted in unitary assembly upon an upright 158 along side of the crank shafts 116 on stage 6. The travel of the arm 144 laterally from a position where it is engageable by the cam 145 to a position out of the path of the cam is best shown in Fig. 20.

In Fig. 25 I have shown the limit switch G, and its operating mechanism with relation to the chain grip and housing 12.

Referring again to Fig. 5, the relative position of the apparatus illustrated therein represents the initiation of the elevation of the swing pipe nozzles 20 due to the energization of the clutch 70 K by the closing of the switch C. At this time the switch D is open. The switch D is in series with the solenoid coil of a solenoid operated valve I and since the solenoid coil of the valve is de-energized the valve member 161 will lie in the pos- 75

tion shown in full lines by virtue of the action of a spring 162 acting to retract the solenoid plunger 163. With the valve 161 in the position shown in Fig. 5 oil under pressure from an oil pump P driven by an electric motor J, in constant operation during the functioning of the barrel washer, may pass through the valve by way of oil conducting pipes 165, 166 and 167 and into the rearward end of the cylinder 64 to urge the piston 63 toward its dotted line position. The oil from in front of the piston 63 returns through the valve to the inlet side of the pump through pipes 168 and 169.

It will be noted that a constriction in the pressure feed pipe 165 between the outlet side of the pump and the valve I is formed by introducing a short section of relatively small feed pipe 171 thereby restricting the rate of flow of the oil under pressure through the valve and into the cylinder 64 and that a by-pass 172 is provided about the feed pipe 171 having connected in series therewith a solenoid operated shut-off valve H adapted when the solenoid coil is energized to lie in open position. The solenoid coil of the valve H is connected in series with the power line and a pair of limit switches E and F which are normally closed and which when either are opened will serve to de-energize the solenoid coil of the valve H to close the valve and therefore the by-pass 172. The switches E and F are located adjacent to the opposite ends of travel of the conveyor chain grip exteriorly of the housing 12 as shown in Fig. 24. Each has a laterally extending shaft 175 provided with an arm 176 and roller 177 at the outer end of the arm so arranged in the path of the chain grip that when the grip approaches either of its limits of travel the adjacent of the switches E or F will open to de-energize the coil of the solenoid valve H and close the by-pass 172 to reduce the rate of flow of oil to the grip operating hydraulic piston 63 thereby decelerating the rate of travel of the chain grip. The provision of this feature in my improved barrel washing machine permits of a relatively high rate of travel of the conveyor chain during the major part of its movement without the danger of damage to the machine through stopping the chain too abruptly as would probably occur without automatic deceleration near the limits of chain grip travel. The limit switch E serves chiefly to prevent damage to the chain grip at the time of its engagement with the retardation mechanism illustrated in Figs. 10 to 12.

With reference to Fig. 3 the return movement of the chain grip occupies a portion of the complete operating cycle as indicated at 177, i. e., substantially one-third of the time required to carry out a complete revolution of the crank shafts 116 accompanied by the introduction and withdrawal of the spray nozzles to and from the barrels BB on stages 4 and 6. The angle 178 on Chart 3 represents the time required to draw the chain grip with the conveyor chain forwardly one stage length. This latter time interval alternates with the time interval during which crank shaft movement takes place as governed by the operation of the magnetic clutch K and switch C.

Referring again to Fig. 5, a single control switch AA may be employed, if desired, to simultaneously set in operation all portions of the electrical control circuit and for the purpose of safety a pair of switches B may be employed in series with the control circuit of the magnetic clutch K, one switch being located at each end of the washing machine in a convenient posi-

tion so that the operator may at any time open either of the switches B to cause further movement of the swing pipe nozzles to cease. As an additional safeguard a pair of switches A may be employed in series with the circuit controlling the pump motor J so that when either of the switches A are opened further operation of the carriage may cease. This latter feature is of particular importance should any of the barrels become out of place while the chain is travelling through the housing 12. The switches A are preferably located adjacent to the switches B.

From the position shown in Fig. 5 the chain grip will advance to its dotted line position where it may remain throughout that portion of the cycle of operation represented at 177 in Fig. 3. As soon as the chain grip has moved out of engagement with the bell crank 147, the limit switch G will open and the solenoid M will become de-energized and caused to assume its dotted line position. At this time the cam 145 will be sufficiently out of range of the arm 144 to permit the arm to shift to the left under the influence of the spring 146. When the crank shaft 116 has completed one revolution accompanied by the introduction of the spray nozzles in the barrels on stages 4 and 6 as heretofore described the cam 145 will again engage with the arm 144 to lift the arm thus opening the switch C to de-energize the clutch K and stop further rotation of the crank shaft and to close the switch D causing the solenoid operated valve I to reverse its position and conduct oil from the pressure side of the pump P into the forward end of the cylinder 64 to drive the chain grip on its chain draft stroke. The drive shaft 115 and crank shaft 116 will remain stationary until the draft movement of the conveyor chain is completed and the chain grip through the instrumentality of the bell crank 147 has closed the switch G to energize the solenoid M thus shifting the arm 144 off of the cam 145 to reverse the position of the switches C and D thereby reestablishing the relative positions of the parts and circuits as shown in Fig. 5 preparatory to the next succeeding cycle of opera-

tion. Inasmuch as the filtration of water for washing large numbers of barrels represents a considerable expense when carried out on a large scale as in a barrel washing machine as herein described, I have provided a switch 181 connected in series with the motor 182 of the pump 37 through a circuit 183 in series with the power line PL which is adapted to be closed through the instrumentality of a switch operating arm 184 actuated by cam 185 located on the crank shaft 116 of the stage 6 (see Fig. 5). The cam 185 functions to maintain the switch 181 closed throughout that portion of the revolution of the crank shaft 116 during which the distributing heads 106 of the nozzles are actually within the barrels BB in their adjacent stages. At X in Figs. 4 and 5 I have indicated the portions of this circuit which are joined.

Hydraulic grip carriage and nozzle operating mechanism

In Fig. 26 I have illustrated another embodiment of the conveyor grip carriage and spray nozzle operating and control mechanism. The operation and function thereof is analogous to that of the mechanism illustrated in Fig. 5 but differs in that the electrical circuits, switches and electrical apparatus are replaced by hydraulic circuits, valves and hydraulically operated mechanism.

In this embodiment of the invention the conveyor grip carriage is operated by the hydraulic piston 63 under influence of fluid pressure in the cylinder 64 provided by the pump P1 controlled by a fluid operated control valve CV. The two crank shafts 116 for stages 4 and 6 respectively may be replaced by a single crank shaft 116a extending through both of the stages and carrying the two pairs of crank arms 119, associated with spray nozzles 17 and 20 respectively. The crank shaft 116a may be operated by a hydraulic motor CR including a piston 188 having a rack 186 fixed thereto engageable with a pinion 187 on the crank shaft. A ratio between pinion, rack and piston stroke is established such as to cause the crank shaft 116a to rotate 180° during a complete stroke, in either direction of the motor piston 188.

Fluid under pressure for operating the motor CR may be provided by a pump P2, driven with the pump P1, by the electric motor J. A valve NV serves to control the motor CR and hence the rise and fall of the internal spray nozzles 17 and 20 (Fig. 13).

The control valves NV and CV are responsive in operation to fluid pressure from a small gear pump unit PV which may be built into the pump P1. A mechanically operated valve MV is employed for controlling, in part, the operation of the valves NV and CV. The valve MV may be of the type wherein the valve member is normally urged to one limit of its movement by a spring 189 engaging with the stem 190 of the valve. An arm 191 fixed to the crank shaft 116a is so arranged as to depress the valve stem 190 against the force of the spring 189 when the crank shaft 116a is in a position to locate the internal spray nozzles 17 and 20 in their lowermost positions, as shown in full lines in Fig. 13.

The valve NV is provided with a valve stem 192 which may extend parallel with the crank shaft 116a at a short distance therefrom and which is normally under the influence of a compression spring 193 tending to urge the valve through its stem 192 to the opposite end of its travel from that position in which the valve is illustrated. A flanged collar 194 fixed upon the valve stem 192 and engageable with a latch 195 pivotally mounted at 195a relative to the valve NV, serves at times to retain the valve in the position shown in Fig. 26 against the force of the spring 193. When the arm 191 upon the crank shaft 116a is moved to the dotted line position as during elevation of the spray nozzles 17 and 20, the latch 195 will be released from engagement with the collar 194 by the pressure of the arm against the latch to cause the valve NV to shift under force of the spring 193 and thereupon reverse the flow of fluid under pressure from the pump P2 into crank shaft fluid motor CR.

The control of fluid under pressure from the pump PV into the area 196 of the valve NV and into the operating cylinders 197 and 198 of the valve CV is carried out by the mechanically operated valve MV.

The apparatus, as illustrated in Fig. 26, represents the grip carriage at the end of its draft stroke. The piston 63 has passed beyond the point of communication between a conduit 201 and the cylinder 64 so that high pressure operating fluid from within the cylinder 64 has become effective, through the conduit 201, the valve cylinder 198 and a resistance valve 202 to urge the valve NV to the full line position shown

against the force of the spring 193, thereby causing the latch 195 to engage with the collar 194 and retain the valve in the position shown. For this purpose the collar engaging portion of the latch 195, at that side facing the valve NV, may be rounded, as shown, so that the outermost flange of the collar 194 will lift the latch in its travel to the position of Fig. 26. Fluid under pressure from the pump P2 may now pass through the valve NV to the rearward end of the piston 188 of the crank shaft fluid motor CR to drive the rack 186 outwardly, thus elevating the nozzles 17 and 20 into the barrels BB on the conveyor 10.

As soon as the crank shaft 116a has completed a 180° movement thus bringing the nozzles 17 and 20 to the limit of their travel in the barrels BB, the arm 191 having arrived at its dotted line position, will release the latch 195 from engagement with the collar 194 and the spring 193 will cause the valve NV to shift from its full line position to the opposite end of its travel thereby reversing the flow of fluid under pressure from the pump P2 to the crank shaft fluid motor CR. The crank shaft 116a will thereupon reverse its movement thus to lower the nozzles out of the barrels. With the arm 191 moved away from the stem 190 and in the dotted line position shown in Fig. 26, the spring 189 will force the stem 190 outwardly to move the valve MV to a position opposite to that shown in Fig. 26. With the valve MV in this position, fluid from a pump PV will pass through the valve MV and enter the cylinder 197 of the valve CV and thereby move the element 204 to the right in the position opposite to that shown in Fig. 26. With the valve element 204 in the last named position, fluid from the pump P1 will pass through the valve CV and enter the forward end of the cylinder 64 and force the piston 63 rearward moving the chain grip to the dotted line position shown in Fig. 26. Upon arrival of the nozzles at the lowermost position of their travel the nozzles will lie entirely out of alignment with the moving elements of the conveyor mechanism, at which time the arm 191 acting upon the valve stem 190 of the valve MV will cause the valve again to assume the position shown in full lines. This position of the valve MV will cause fluid under pressure from the pump PV to be conducted to the cylinder 198 of the valve CV thereby to shift the valve to the position shown and admit fluid under pressure from pump P1 rearwardly of piston 63 so that the conveyor chain and the barrels BB supported thereupon may be drawn forwardly by engagement of the grip carriage therewith in the manner heretofore described whereupon the apparatus is in readiness for a repetition of the cycle of operation described and at each cycle will function to cause a group of the barrels BB to advance one stage length through the barrel washing apparatus within the housing 12.

In the hydraulic embodiment of the operating and control mechanism the grip carriage may be provided with a pair of cams 206, one at each end of the carriage engageable with cam wheels 207, carried by push rods 208, located near the remote ends of the path of movement of the grip carriage. The push rods 208 may be each engageable with a bell crank 209, each bell crank having an arm 210 in registration with collars 211 fixed to a rod 212 extending along the path of travel of the grip carriage and connected at one end with a plunger valve 213. The plunger 75

valve 213 when moved to the position shown in full lines, as by engagement of the cam 208 with the cam roller 207, acts to cut-off fluid under pressure from the pump PV into a pressure operated control mechanism 214 of the pump P1 which functions to decrease the fluid pressure at the outlet of the pressure pump P1 thereby slowing the speed of the grip carriage. The grip carriage is thus caused to decelerate when approaching the limit of its stroke in either direction, in substantially the same manner as occurs in Fig. 5 through the instrumentality of the switches E and F and the by-pass solenoid operated valve H.

In Fig. 27 I have illustrated one form of the pressure control mechanism 214. This mechanism may comprise a by-pass valve 215 having a movable valve member 216 which when urged from the position shown inwardly of the cylindrical chamber 217 against the force of spring 218 serves to shut off by-pass communication between the outlet and inlet pipes 219 and 221 of the pump P1. The valve member 216 is caused to move inwardly during normal operation of the conveyor operating mechanism 63-64 by fluid under pressure admitted to the cylinder 222 through the pipe 223 communicating with the valve 213 through the medium of a piston 224 within the cylinder 222 carried by the valve member 216. Obviously, other types of pressure control mechanism may be employed for the purpose intended, wherein pressure from the pump PV may be used to close the by-pass between the outlet and inlet pipes of the conveyor operating pump P1.

In the flow diagram of Fig. 26 I have included a control valve 226 in the pipe line 223 so that the rate of response of the pressure control valve 214 may be governed to some extent. There is also included in the fluid flow circuit check valves 227 and 228, the former being in the line interconnecting the valves NV, MV and CV, the latter being in the feed line between the pump PV and the valve MV.

Although the present invention has been described in connection with the details of specific embodiments thereof, it is not intended that such details shall be regarded as limitations upon the scope of the invention, except in so far as included in the accompanying claims.

I claim:

1. In a barrel washing machine, an endless conveyor, said conveyor comprising barrel supporting means located in a plane substantially 55 10° from the horizontal, and adapted to support a plurality of barrels in a tilted position with their bung holes lowermost, automatic means for advancing the conveyor a predetermined distance during a portion of each complete operating cycle 60 of said machine, a plurality of spray nozzles, a plurality of arcuated swing pipes, said plurality of spray nozzles being mounted on said plurality of arcuated swing pipes, said plurality of arcuated pipes being secured to a pivotally mounted 65 feed pipe, whereby said plurality of spray nozzles and said plurality of arcuated swing pipes are movably mounted in registration with certain of the tilted barrels of said conveyor when the conveyor is at rest, and means operable to move said nozzles within the interior of said barrels and to withdraw them during the remaining portion of 70 said complete operating cycle.

2. In a barrel washing machine as described in claim 1 a plurality of funnel shaped members 75 fixed to said conveyor and adapted to be received

partially within said bung holes when the barrels are placed upon the conveyor and to locate the barrels thereupon in predetermined relationship with the conveyor.

3. In a barrel washing machine, an endless 5 conveyor, said conveyor comprising barrel supporting means located in a plane substantially 10° from the horizontal and adapted to support a plurality of barrels in a tilted position with their bung holes lowermost, barrel heating, washing and rinsing means occupying stages of equal length linearly equally spaced at intervals of one stage length along the path of movement of said conveyor, means for advancing the conveyor during 15 each cycle of operation of the machine a distance 15 equal to one stage length whereby the barrels on said conveyor are advanced progressively to said barrel heating, washing and rinsing stages, a plurality of spray nozzles mounted on a plurality of 20 arcuated swing pipes located at certain of the stages, said plurality of arcuated swing pipes being associated with a pivotally mounted feed pipe, said arcuated swing pipes being adapted for registration, when the conveyor is at rest, with the bung holes of barrels on the adjacent portions of 25 said conveyor, and means operable when said conveyor is at rest to move said nozzles within the interior of the barrels and to withdraw them, said last named means being operably responsive to a 30 function of said conveyor advancing means.

4. In a barrel washing machine, a conveyor mounted for straight line movement and adapted to support a plurality of barrels in substantially upright position thereupon, barrel pre-heating, 35 washing and rinsing stages located in series array along the path of travel of said conveyor and occupying linearly equal spaces along the path of conveyor travel, a movable conveyor grip, a dog on said grip adapted to engage said conveyor during movement of the grip in one direction to move the 40 conveyor therewith, automatic means for drawing the grip, together with the conveyor, a distance equal to one stage length to advance all of the barrels on said conveyor from one to the next succeeding of the stages and for returning the 45 grip preparatory to its next conveyor draft function, means, including a pivotally mounted feed pipe and a plurality of arcuated swing pipes and spray nozzles associated therewith, operable to internally wash and internally rinse the barrels 50 at certain of said stages, said swing pipes and spray nozzles being adapted to move into close proximity to the barrels on said conveyor during the treatment of said barrels, means for actuating said pivotally mounted feed pipe, including a 55 motor driven crank shaft operatively connected to said feed pipe and provided with a cam, and means actuated by said cam on said motor driven crank shaft rendering the last named means inoperative during the movement of said conveyor. 60

5. In a barrel washing machine, a conveyor mounted for straight line movement and adapted to support a plurality of barrels in substantially upright position thereupon, barrel pre-heating, washing and rinsing stages located in series array 65 along the path of travel of said conveyor, and occupying linearly equal spaces along the path of conveyor travel, a movable conveyor grip, a dog on said grip adapted to engage said conveyor during movement of the grip in one direction to move the conveyor therewith, automatic means for drawing the grip, together with the conveyor, a distance equal to one stage length to advance all of the barrels on said conveyor from one to the next succeeding stages and for returning the 70 75

- grip preparatory to its next conveyor draft function, means, including a pivotally mounted feed pipe and a plurality of arcuated swing pipes and spray nozzles associated therewith, operable to internally wash and internally rinse the barrels at certain of said stages, said swing pipes and spray nozzles being adapted to move into close proximity to the barrels on said conveyor during the treatment of said barrels, means for actuating said pivotally mounted feed pipe, including a motor driven crank shaft operatively connected to said feed pipe and provided with a cam, means actuated by said cam on said motor driven crank shaft rendering the last named means inoperative during the movement of said conveyor, and automatic means for decreasing the speed of said conveyor grip as it approaches either of its limits of travel.
6. In a barrel washing machine, nozzles for spraying a preheating fluid on said barrels, nozzles for spraying a washing solution exteriorly and interiorly of the barrels, nozzles for spraying rinse water exteriorly of the barrels, nozzles for spraying rinse water interiorly of the barrels, sump reservoirs for the preheating nozzles, the washing nozzles and the rinse nozzles respectively, means for supplying hot filtered water to the interior barrel rinsing nozzles, means for pumping the used rinse water from the rinse reservoir to the exterior rinsing nozzles, means for pumping hot water from the rinse reservoir into the preheating reservoir and for pumping the water therefrom to the preheating nozzles, means for supplying the washing reservoir with the washing solution, means for pumping washing solution from the washing reservoir to the washing nozzles and means for transferring heat from the used preheating water to the filtered water prior to its admission to said interior rinse nozzles.
7. In combination, a conveyor member mounted for movement along a fixed course of travel, conveyor grip means for advancing said conveyor, said conveyor grip means comprising a conveyor grip carriage mounted for reciprocation along a path parallel to the movement of said conveyor, hydraulic means for actuating said conveyor grip carriage, a valve for controlling said hydraulic means, apparatus for treating articles placed upon said conveyor including a pivotally mounted feed pipe and a plurality of arcuated swing pipes and spray nozzles associated therewith, said swing pipes and spray nozzles being adapted to move into close proximity to the articles on said conveyor during the treatment of said articles, means for actuating said pivotally mounted feed pipe, means for operating said valve, said last named means being actuated by said means for actuating said pivotally mounted feed pipe whereby the movement of the conveyor and the functioning of the treating apparatus may bear a fixed relationship as to time.
8. In combination, a conveyor member mounted for movement along a fixed course of travel, conveyor grip means for advancing said conveyor, said conveyor grip means comprising a conveyor grip carriage mounted for reciprocation along a path parallel to the movement of said conveyor, hydraulic means for actuating said conveyor grip carriage, a valve for controlling said hydraulic means, apparatus for treating articles placed upon said conveyor including a pivotally mounted feed pipe and a plurality of arcuated swing pipes and spray nozzles associated therewith, said swing pipes and spray nozzles adapted to move into close proximity to the articles on said conveyor during the treatment of said articles, said swing pipes and spray nozzles being adapted to move into close proximity to the articles on said conveyor during the treatment of said articles, means for actuating said pivotally mounted feed pipe, means for operating said valve, said last named means being actuated by said means for actuating said pivotally mounted feed pipe whereby the movement of the conveyor and the functioning of the treating apparatus may bear a fixed relationship as to time.
9. In combination, a conveyor member mounted for movement along a fixed course of travel, conveyor grip means for advancing said conveyor, said conveyor grip means comprising a conveyor grip carriage mounted for reciprocating along a path parallel to the movement of said conveyor, hydraulic means for actuating said conveyor grip carriage, a valve for controlling said hydraulic means, apparatus for treating articles placed upon said conveyor including a pivotally mounted feed pipe and a plurality of arcuated swing pipes and spray nozzles associated therewith, said swing pipes and spray nozzles being adapted to move into close proximity to the articles on said conveyor during the treatment of said articles, means for actuating said pivotally mounted feed pipe, including a hydraulic driven crank shaft operatively connected to said feed pipe and provided with an arm, and hydraulic means, including an operating valve actuated by said arm on said hydraulic driven crank shaft, for controlling the operation of said first named valve whereby the movement of the conveyor and the functioning of the treating apparatus may bear a fixed relationship as to time.
10. In a barrel washing machine, a movable conveyor, said conveyor comprising barrel supporting means located in a plane substantially 10° from the horizontal, said barrel supporting means being adapted to support a plurality of barrels with their longitudinal axes substantially 10° from the vertical plane and with their bung holes located at the lowermost portion, conveyor gripping means for advancing the conveyor a predetermined distance during a complete cycle of the operation of said conveyor, said conveyor gripping means including a conveyor grip carriage mounted for reciprocation along a path parallel to the movement of said conveyor, barrel treating stages spaced along the path of said conveyor, housing means at each of said barrel treating stages, a plurality of spray nozzles mounted on a plurality of arcuated swing pipes, said arcuated swing pipes being secured to a pivotally mounted feed pipe located at certain of said stages said plurality of spray nozzles and said arcuate swing pipes being adapted for registration when the conveyor is at rest with the bung holes of the barrels on the adjacent portion of said conveyor, and means operable when said conveyor is at rest to move said nozzles and arcuated swing pipes within the interior of said barrels and to withdraw them, said last named means being operably responsive to a functioning of said conveyor advancing means.
11. In a barrel washing machine, an endless conveyor, said conveyor comprising barrel supporting means located in a plane substantially 10° from the horizontal and adapted to support a plurality of barrels in a tilted position with their bung holes lowermost, barrel heating, washing and rinsing means occupying stages of equal length linearly equally spaced at intervals of one stage

length along the path of movement of said conveyor, means for advancing the conveyor during each cycle of operation of the machine a distance equal to one stage length whereby the barrels on said conveyor are advanced progressively to said barrel heating, washing and rinsing stages, a plurality of external spray nozzles located at certain of the stages, a plurality of internal spray nozzles mounted on a plurality of arcuated swing pipes located at certain of the stages, said plurality of arcuated swing pipes being associated

with a pivotally mounted feed pipe, said arcuated swing pipes being adapted for registration when the conveyor is at rest, with the bung holes of barrels on the adjacent portions of said conveyor, and means operable when said conveyor is at rest 5 to move said nozzles within the interior of the barrels and to withdraw them, said last named means being operably responsive to a function of said conveyor advancing means.

10
